Primary Examiner — Janice Patyk(74) *Attorney, Agent, or Firm* — Plumsea Law Group, LLC(57) **CLAIM**

The ornamental design for a loudspeaker as shown and described.

DESCRIPTION

FIG. 1 is a top perspective view of a loudspeaker showing the new design, with the handle in a raised, top position; FIG. 2 is a front elevational view thereof, with the handle in a folded, rear position;

FIG. 3 is a rear elevational view thereof;

FIG. 4 is a side elevational view thereof;

FIG. 5 is an opposite side elevational view thereof;

FIG. 6 is a top view thereof; and,

FIG. 7 is a bottom view thereof.

The broken lines within the handle that run parallel or perpendicular to the length of the handle form no part of the claimed design.

1 Claim, 7 Drawing Sheets(56)
